UNITED STATES PATENT OFFICE

HENRY L. COX, OF SOUTH CHARLESTON, AND PAUL S. GREER, OF CHARLESTON, WEST VIRGINIA, ASSIGNORS TO CARBIDE & CARBON CHEMICALS CORPORATION, A CORPORATION OF NEW YORK

PRESERVATION OF ETHYL ETHER

No Drawing.

Application filed February 26, 1932. Serial No. 595,420.

This invention provides an improvement in the preservation of ethyl ether.

Ethyl ether has numerous applications which necessitate the preparation and preservation of this compound in a state of extreme purity. It is possible to control satisfactorily the original state of purity of the ether by the processes by which it is made. However, ethyl ether under all ordinary storage, shipping, and handling conditions, undergoes spontaneous deterioration with the formation of difficultly removable deleterious impurities. It is almost universal practice to use glass containers for the storage of materials which are to be kept in a state of extreme purity. Ethyl ether tends to deteriorate even in glass containers.

The principal object of our invention is to provide an improvement for the preservation of ethyl ether whereby it may be shipped and stored without becoming contaminated with objectionable impurities. Another object is to provide preserving agents by means of which ethyl ether may be preserved in a pure state.

We have discovered that the objects of this invention may be attained by subjecting the ether to be preserved to the action of a metallic preserving agent of the group consisting of metallic chromium, metallic nickel, and iron alloys containing both chromium and nickel. The ethyl ether may be subjected to the action of these preserving agents in any desired manner, as for example, a quantity of the preserving agent may be added to the ether in an ordinary container, such as one made of glass; the ether may be stored in a container formed entirely of the metallic preserving agent; or a large part of the interior surface of an ordinary container may be formed of the preserving agent as plating, flashing or any other desired form.

The effectiveness of our improvement in preserving ether is shown by the fact that it will keep ethyl ether in a pure state, and that even when originally contaminated with impurities the ether after being stored in accordance with our invention may show a decrease in the content of impurities.

The following examples illustrate the invention:

1. One quart of ethyl ether was stored for two months in a clear glass bottle in which was immersed a strip of an iron alloy containing 18% Cr and 8% Ni. At the beginning of the period the ether sample by test was found to contain a small quantity of impurities, and at the end of the two months period the ether tested free from impurities. An identical sample of ether placed in a glass bottle without the strip of alloy was found to contain an objectionable amount of impurities after 24 hours of storage.

2. Two identical one quart samples of ethyl ether free from impurities were stored in glass bottles. A strip of chromium plated aluminum was placed in one bottle and nothing was added to the other. The bottle containing the chromium plated strip tested free from impurities throughout the test period which was two months. The other sample of ether developed an objectionable quantity of impurities after 24 hours of storage.

3. Identical samples of pure ethyl ether were placed in glass bottles to one of which a few pieces of scrap nickel were added. After standing for 6 weeks the sample which was subjected to the action of nickel was substantially free from detrimental impurities, while the sample kept in a plain glass bottle contained an objectionable quantity of impurities after standing for 24 hours.

We claim:

1. The improvement in the preservation of ethyl ether, which ether tends to deteriorate under ordinary storage conditions even in glass containers, which consists in subjecting the ethyl ether to the action of a metallic substance selected from the group composed of metallic chromium, metallic nickel, and iron alloys containing both chromium and nickel whereby to diminish the content of detrimental impurities.

2. The improvement in the preservation of ethyl ether, which ether tends to deteriorate under ordinary storage conditions even in glass containers, which consists in

subjecting the ethyl ether to the action of a metallic substance selected from the group composed of metallic chromium, metallic nickel, and iron alloys containing about 18% of chromium and about 8% of nickel whereby to diminish the content of detrimental impurities.

3. The improvement in the preservation of ethyl ether, which ether tends to deteriorate under ordinary storage conditions even in glass containers, which consists in subjecting the ethyl ether to the action of iron alloys containing both chromium and nickel whereby to diminish the content of detrimental impurities.

4. The improvement in the preservation of ethyl ether, which ether tends to deteriorate under ordinary storage conditions even in glass containers, which consists in subjecting the ethyl ether to the action of iron alloys containing about 18% of chromium and about 8% of nickel whereby to diminish the content of detrimental impurities.

5. The improvement in the preservation of ethyl ether, which ether tends to deteriorate under ordinary storage conditions even in glass containers, which consists in subjecting the ethyl ether to the action of metallic chromium whereby to diminish the content of detrimental impurities.

6. The improvement in the preservation of ethyl ether, which ether tends to deteriorate under ordinary storage conditions even in glass containers, which consists in subjecting the ethyl ether to the action of metallic chromium in the form of a chromium plated material whereby to diminish the content of detrimental impurities.

7. The improvement in the preservation of ethyl ether, which ether tends to deteriorate under ordinary storage conditions even in glass containers, which consists in subjecting the ethyl ether to the action of metallic nickel whereby to diminish the content of detrimental impurities.

8. The improvement in the preservation of ethyl ether, which ether tends to deteriorate under ordinary storage conditions in subjecting the ethyl ether to the action of the surfaces which comprises a substantial proportion of metallic nickel whereby to diminish the content of detrimental impurities.

In testimony whereof, we affix our signatures.
